UNITED STATES PATENT OFFICE

CLARENCE F. McCLEARY, OF PRESCOTT, ARIZONA

MUSICAL INSTRUMENT

Application filed May 17, 1930. Serial No. 453,298.

This invention relates to a musical instrument which I call "Rondolin", the general object of the invention being to provide a rotary shaft, with means for rotating the same in one direction by the foot of the user and in another direction by a spring, with two circular members on the shaft carrying bridge pieces which support a plurality of strings connected with the shaft and the bridge pieces so that the strings can be played upon by one or more bows between the circular members and the shaft rotated to bring the desired strings to the playing position.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation of the device, with parts in section.

Figure 2 is a section on line 2—2 of Figure 1.

Figure 3 is a section on line 3—3 of Figure 1.

Figure 4 is a section on line 4—4 of Figure 1.

Figure 5 is a section on line 5—5 of Figure 1.

Figure 6 is a section on line 6—6 of Figure 1.

Figure 7 is a detail view showing the foot on the rear supporting member.

In these views, the numeral 1 indicates a shaft which carries the members A and B. These members are of circular shape and each member comprises the end parts 2 and 3, the rim 5 and the radial supports C which connect the rim with the shaft. Each support C consists of a piece 6 having its inner end fastened in a slot in the shaft and the arms 7 connected with the outer end of each piece 6, with their outer ends connected with the rim. Each arm 7 tapers outwardly both

in thickness and in width so that these arms are spaced from the end members 2 and 3, as shown in Figure 1. Rings 8 are connected with the rim and the outer peripheries of the members 2 and 3, as shown in Figure 1. 55 Each member 2 and 3 is formed with a central opening 9 of much greater diameter than the shaft and the member 3 has its opening of smaller diameter than the opening in the member 2. A ring shaped bridge 10 is fastened to each member 2 and has its inner periphery flush with the wall of the opening in said member 2. The members A and B are so placed on the shaft that the end members 2 face each other, as shown in Figure 1. 65

Each bridge piece carries a plurality of small eye bolts 11 which are radially arranged in the bridge piece, with the eyes innermost and with the nuts 12 on the bolts outermost. A plurality of wires or strings 13 pass 70 through the eyes of the bolts on the bridge piece of member B and have their lower ends anchored to the shaft an appreciable distance below the member B by the pins 14. Said wires pass through the opening in the member A and have their upper ends fastened to the tuning pins 15 which are rotatably supported by the shaft adjacent the upper end thereof. A plurality of wires or strings 16 pass through the eyes of the bolts of the 75 bridge piece of member A and have their upper ends anchored to the upper part of the shaft, as shown at 17, these wires or strings passing through the opening of member B with their lower ends fastened to the tuning pins 18 in the lower end of the shaft. 80

As shown in Figures 2 and 3, I prefer to use twenty-two of the strings or wires 13 and fifteen of the strings or wires 16 and as shown in these figures, the wires 13 are arranged equal distances apart, while the wires 16 are arranged in groups of two and three. Thus the device is chromatically strung like a piano, with the twenty-two strings 13 completing three octaves. For example, the first string is C, one octave below middle C on the piano, the next C above is the eighth string and the next C above is the fifteenth and the next C above is the twenty-second string. As shown in Figure 3, the strings on the upper 85 90 95 100

member A are arranged in groups of two and three the same as the black keys on a piano. The strings are spaced apart sufficiently for any single string to be played without conflicting an adjacent string, with the strings of one member passing midway between a pair of strings of the other member. I prefer to form the shaft and the parts of the members A and B of hard wood, each member 2 being preferably of spruce. The members 2 and 3 taper in thickness from their inner edges to their outer edges, as shown.

The shaft is rotatably supported by a frame D, the upper part of which has a screw 19 therein which fits in a straight hole in the top of the shaft and the lower part of which has a conical pin 20 therein which fits in a conical hole in the lower end of the shaft. The frame comprises a post 21 carrying an arm 22 at its upper end which supports the pin 20, a diagonal post 23 which supports the arm 24 which carries the screw 19 and the brace 25 which has its ends passing through slots in the posts 21 and 23 and cleats 26 thereon engaging the post, with pins 27 passing through holes in the ends of the brace 25 and engaging the posts for holding the parts in assembled position. A lever 28 is pivoted at its upper end to the brace 25, as shown at 29, and a stop pin 30 on said brace limits the forward movement of the lever. A stationary arm 31 is fastened to the lower part of the brace and a spring 32 has one end connected with the outer end of the arm 31 and its other end is connected to the bottom of a groove 33 formed in the lower end of the shaft. A cable 34 is fastened in the bottom of a groove 35 in the shaft arranged above the groove 33 and the other end of the cable is connected to the lever, as shown at 36. This lever has a foot piece 37 at its lower end which is provided with a heel piece 38 so that the operator can place his foot on the foot piece with his heel in the space formed by the piece 38 to permit movement of the lever. The spring and cable are oppositely wound in the grooves of the shaft, with the cable on one side of the brace and the spring on the opposite side, as shown in Figure 5.

The operator sits in front of the device with his foot on the foot piece of the lever 28 and by pressing rearwardly the lever, the cable, unwinding from the shaft, will rotate the same in one direction and in this movement, the spring is wound on the shaft so that when pressure is released from the lever, the spring will turn the shaft in the opposite direction. Thus the operator can place the strings in any desired position by moving the lever with his foot. Thus portions of the strings between the members A and B are played upon with one or two bows. The parts are so arranged that the full backward movement of the lever will result in a complete revolution of the shaft. The strings are adjusted by slackening and tightening the nuts

on the eye bolts and by removing the pins 27, the frame can be knocked down and the parts placed in a case or the like. The first and second octaves or lower octaves are strung with wound strings. The parts of the strings that vibrate or produce the tone are those parts which are located between the circular bridges and the tuning pins. The third or upper octave is strung with music wire of the required size and the strings of that octave are gradually shortened by placing the tuning pins closer to the back of the instrument bodies A and B until the last or highest pitched string has a length from its eye bolt to the tuning pin of about 14½ inches.

Attention is called to the fact that the supporting structures C do not contact either the end pieces 2 or 3, so that these pieces are free to vibrate and all the carriers or eye bolts are of equal distance from the rim 5, thus giving each string its due quota of sound board from which to draw its tone. The tone productions are equally good at any point between the two members A and B. The strings can be plucked with the fingers of one hand while using a bow with the other hand.

Plates of black and white, not shown, may be placed on the shaft under the strings to represent keys like those of a piano so that the player can readily find the proper strings. The tension on the strings on the circular bridge pieces is from the outside toward the center, which adds much to the strength of resistance and as the strings extend entirely around the bridge piece, the tension or draft of strings is balanced.

The member 23 is provided with a foot part 23' which contacts the floor at two points so that the device is supported at three points, one in front and two at the rear. The lower end of the member 23 has a tapered lower end which fits in a tapered opening in the member 23' so that the foot part can be readily removed when the device is knocked down.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A musical instrument of the class described comprising a shaft, means for rotatably supporting the shaft, a pair of bodies connected with the shaft, with circular spaces between the bodies and the shaft, a bridge piece carried by each body, strings having their ends connected with the shaft and passing through the circular spaces, a circular bridge piece carried by each body and string supporting means carried by the bridge

pieces, some of the strings being supported by the bridge piece of one body and the remaining strings being supported by the other bridge piece.

- 6 2. A musical instrument comprising a shaft supported for rotary movement, a pair of circular bodies supported in spaced relation from the shaft with spaces between the bodies and the shaft, a circular bridge piece carried by each body, eye members carried by each bridge piece, strings passing through the eye members of one of the bridge pieces, strings passing through the eye members of the other bridge piece, said strings passing through the spaces between the bodies and the shaft, means for fastening one end of each string to the shaft and a rotary member connecting the other end of each string to the shaft.
- 10 3. A musical instrument comprising a shaft supported for rotary movement, a pair of circular bodies supported in spaced relation from the shaft with spaces between the bodies and the shaft, a circular bridge piece carried by each body, eye members carried by each bridge piece, strings passing through the eye members of one of the bridge pieces, strings passing through the eye members of the other bridge piece, said strings passing through the spaces between the bodies and the shaft, means for fastening one end of each string to the shaft, a rotary member connecting the other end of each string to the shaft and means for adjusting the eye members.
- 15 4. A musical instrument comprising a shaft supported for rotary movement, a pair of circular bodies supported in spaced relation from the shaft with spaces between the bodies and the shaft, a circular bridge piece carried by each body, eye members carried by each bridge piece, strings passing through the eye members of one of the bridge pieces, strings passing through the eye members of the other bridge piece, said strings passing through the spaces between the bodies and the shaft, means for fastening one end of each string to the shaft, a rotary member connecting the other end of each string to the shaft and foot operated means for rotating the shaft.
- 20 5. A musical instrument comprising a shaft supported for rotary movement, a pair of circular bodies supported in spaced relation from the shaft with spaces between the bodies and the shaft, a circular bridge piece carried by each body, eye members carried by each bridge piece, strings passing through the eye members of one of the bridge pieces, strings passing through the eye members of the other bridge piece, said strings passing through the spaces between the bodies and the shaft, means for fastening one end of each string to the shaft, a rotary member connecting the other end of each string to the shaft and foot operated means for rotating the shaft, such

wound in one direction on the shaft and a string having a part wound in an opposite direction on the shaft and a foot lever connected with the string.

- 6 2. A musical instrument of the class described comprising a shaft, a number of bodies supported therefrom, each body consisting of upper and lower end pieces, a rim connecting the outer edges of the pieces together, a number of radial members connected with the shaft, arms connecting the radial members with the rim, each end piece having an opening therein of larger diameter than the shaft, a ring shaped bridge piece on one end piece of each member, strings connected with the shaft and passing through the spaces between the shaft and the bodies, means for attaching the strings to the bridge pieces and means for supporting the shaft.
- 10 7. A musical instrument comprising a shaft, a collapsible frame supporting the shaft in a diagonal position, means whereby the shaft can be rotated in the frame, a pair of circular bodies supported from the shaft, each body having a circular space between itself and the shaft, circular bridge pieces carried by the bodies, with their inner edges flush with the outer walls of the spaces, adjustable eye bolts in each bridge piece, strings passing through the eye bolts of one bridge piece, strings passing through the eye bolts of the other bridge piece, pins for fastening the strings which pass through the eye bolts of the lower body to the lower part of the shaft, rotary pins in the upper end of the shaft to which said strings are connected, pins connecting the strings which pass through the eye bolts of the upper body to the upper part of the shaft and rotary pins in the lower part of the shaft to which said last mentioned strings are connected.

In testimony whereof I affix my signature.
CLARENCE F. McCLEARY.
